(57) **CLAIM**

The ornamental design for a camera, as shown and described.

DESCRIPTION

FIG. 1 is a top, front, right perspective view of a camera showing our new design;

FIG. 2 is a top, front, left perspective view thereof;

FIG. 3 is a bottom, rear, right perspective view thereof;

FIG. 4 is a bottom, rear, left perspective view thereof;

FIG. 5 is a front view thereof;

FIG. 6 is a rear view thereof;

FIG. 7 is a right side view thereof;

FIG. 8 is a left side view thereof;

FIG. 9 is a top view thereof; and,

FIG. 10 is a bottom view thereof.

The evenly spaced broken lines depict portions of the camera in which the design is embodied that form no part of the claimed design. Additionally, the dash-dot broken lines which are shown immediately adjacent to the shaded areas represent the bounds of the claim and form no part of the claimed design.
